UNITED STATES PATENT OFFICE.

GARNETT DUNCAN, OF YELLVILLE, ARKANSAS.

EMBROIDERY-FRAME.

1,079,042.

Specification of Letters Patent. Patented Nov. 18, 1913.

Application filed March 15, 1913. Serial No. 754,605.

To all whom it may concern:

Be it known that I, GARNETT DUNCAN, a citizen of the United States, residing in Yellville, in the county of Marion and State of Arkansas, have invented certain new and useful Improvements in Embroidery-Frames, of which the following is a specification.

This invention relates to embroidery frames of the class in which the material worked on is held between two concentric hoops, and the object of my invention is to so construct the outer hoop that it may be easily placed over the material on the inner hoop without unduly stretching the material or rubbing it and may then be quickly tightened to hold the material firmly in place.

According to my invention I employ a continuous inner hoop of the usual kind and use a divided outer hoop which carries on one end near the line of division a pivoted lever which serves as a handle and which is connected to the end of the hoop on the opposite side of the line of division by a spring in such manner that when the lever is in one position it holds the outer hoop in a distended condition, but when the lever is turned to another position it reduces the diameter of the hoop and holds it on the material carried by the inner hoop.

In the accompanying drawings, Figure 1 is a perspective view of an embroidery frame embodying my improvements showing how it holds the material to be worked on. Fig. 2 is a perspective view of the frame showing the inner and outer hoops with the latter clamped upon the inner hoop. Fig. 3 is a plan view of a portion of the two hoops showing the lever in its clamped position. Fig. 4 is a similar view showing the lever in its outer position with the outer hoop loosened.

The inner hoop A is of the usual form and is continuous. The outer hoop B surrounds the inner one and it is divided as shown at b. When the ends of the divided hoop are separated to the extent shown in Fig. 4 the hoop may be easily arranged over the material carried by the inner hoop without stretching it unduly or rubbing it, but when the ends of the outer hoop are brought closer together, as shown in Fig. 3, the material is tightly clamped between the hoops. One end portion of the outer hoop carries a lever C which is pivotally connected with

a bracket d on the outer hoop near the dividing line of the hoop. If the outer hoop be made of metal the bracket may be formed by providing the hoop with lateral extensions and turning them outward, as shown, to form the bracket. The lever C is provided with a tongue e which is connected at its inner end with the body of the lever and at its outer end it is connected by means of a spiral spring D with the end of the hoop B on the opposite side of the dividing line b. The connection of the inner end of the tongue e with the lever is such as to permit it to turn to a limited extent. Preferably the tongue e is formed integrally with the lever which may be made of spring metal. When the lever is in the position shown in Fig. 4 the end of the tongue e to which the spiral spring D is attached is on that side of the pivot x of the lever next the end of the outer hoop to which the opposite end of the spring D is attached and the spring D is not under tension. At this time the outer hoop is distended and may be easily applied to or removed from the inner hoop, but when the lever is moved to the opposite position, indicated in Figs. 1, 2 and 3, the outer end of the tongue e, to which the spiral spring is attached, is disposed on the opposite side of the pivot x, i. e., on that side of the pivot opposite to the one shown in Fig. 4, and at this time the spiral spring D is distended and the two ends of the hoop are drawn closely together and in such manner as to tightly clamp the material between the two hoops. The arrangement is also such that the lever is held in either of the two positions above mentioned and cannot stop in any other position. In this way when the outer hoop is being applied it is held permanently in its distended position and when once applied it is held permanently and securely in its contracted position.

I claim as my invention:

1. An embroidery frame, comprising an inner hoop, an outer divided hoop, an operating lever pivotally connected with the divided hoop on one side of the dividing line, a tongue on the lever having its inner end disposed between the outer end of the lever and its pivotal connection with the hoop, and a spring connecting the inner end of the tongue with the outer hoop on the opposite side of the dividing line.

2. An embroidery frame, comprising an inner hoop, an outer divided hoop, a lever pivotally connected with the outer hoop near the dividing line and having a spring metal tongue connected with it, a spring connected with the tongue at a point between the outer end of the lever and the pivotal connection thereof with the hoop and which is also

connected with the outer hoop at a point on the opposite side of the dividing line. 14

In testimony whereof, I have hereunto subscribed my name.

GARNETT DUNCAN.
